CLAIM

The ornamental design for a foldable child seat, as shown and described.

DESCRIPTION

FIG. 1 is a side elevation view of a foldable child seat in an unfolded state taken from a left hand side as viewed by an operator;

FIG. 2 is front elevation view of the foldable child seat in an unfolded state;

FIG. 3 is a right side elevation view of a foldable child seat in an unfolded state and a mirror image of the elevation view shown in FIG. 1;

FIG. 4 is a rear elevation view of the foldable child seat;

FIG. 5 is a top plan view of the foldable child seat in an unfolded state;

FIG. 6 is a bottom plan view of the foldable child seat in an unfolded state;

FIG. 7 is a perspective view of the foldable child seat in an unfolded state taken from a top, left and front side perspective;

FIG. 8 is a perspective view of the foldable child seat in an unfolded state taken from a top, front and right side view, and is a mirror image of the perspective view shown in FIG. 7;

FIG. 9 is a left elevation view of the foldable child seat in a folded state;

FIG. 10 is a front elevation view of the foldable child seat in a folded state;

FIG. 11 is a top plan view of the foldable child seat in a folded state; and,

FIG. 12 is a perspective view of the foldable child seat in a folded state taken from a top, right and front side perspective, the perspective view taken from a top, left and front side perspective being a mirror image.

Broken-lines showing other elements of a stroller cart, which elements include a stroller cart frame, a knob on a push handle of the stroller car frame, a lower tray and casters, are for illustrative purposes only and form no part of the claimed design.
